UNITED STATES PATENT OFFICE

150,990

DESIGN FOR A COMBINED FRUIT REAMER AND STRAINER

Carl G. Krieger, Mason City, Iowa

Application April 18, 1947, Serial No. 138,475

Term of patent 14 years

(Cl. D89—1)

To all whom it may concern:

Be it known that I, Carl G. Krieger, a citizen of the United States and a resident of Mason City, in the county of Cerro Gordo and State of Iowa, have invented a new, original, and ornamental Design for a Combined Fruit Reamer and Strainer, of which the following is a specification, reference being had to the accompanying drawing, forming part thereof.

Figure 1 is a perspective view of a combined fruit reamer and strainer, embodying the features of my new design.

Figure 2 is a side elevational view of a scale smaller than that shown in Figure 1.

Figure 3 is a bottom plan view of the same.

I claim:

The ornamental design for a combined fruit reamer and strainer, as shown.

CARL G. KRIEGER.
